(57) **CLAIM**

We claim the ornamental design for a coffee table, as shown and described.

DESCRIPTION

FIG. 1 is a perspective view of the coffee table;
FIG. 2 is a front view thereof;
FIG. 3 is a rear view thereof;
FIG. 4 is a left view thereof;
FIG. 5 is a right side view thereof;
FIG. 6 is a top view thereof; and,
FIG. 7 is a bottom view thereof.
The broken lines are for environmental purposes only and
form no part of the claimed design.
